[57] CLAIM

The ornamental design for a playground rider, as shown and described.

DESCRIPTION

FIG. 1 is a perspective view of a playground rider embodying my new design;

FIG. 2 is a top plan view thereof;

FIG. 3 is a side elevational view thereof, the opposite side being identical; and

FIG. 4 is an end elevational view thereof on a larger scale, the opposite end view being identical.

FIG. 1

FIG. 2

FIG. 3

FIG. 4
